UNITED STATES PATENT OFFICE.

WALTER BULLARD, OF CHICO, CALIFORNIA.

BALING-PRESS.

SPECIFICATION forming part of Letters Patent No. 424,046, dated March 25, 1890.

Application filed August 24, 1889. Serial No. 321,894. (No model.)

To all whom it may concern:

Be it known that I, WALTER BULLARD, of Chico, Butte county, State of California, have invented an Improvement in Baling-Presses; 5 and I hereby declare the following to be a full, clear, and exact description of the same.

My invention relates to the class of baling-presses; and it consists in the constructions, arrangements, and combinations of parts herein-10 after fully described, and specifically pointed out in the claims.

The object of my invention is to provide a compact, effective, and rapidly-operating press.

15 Referring to the accompanying drawings for a more complete explanation of my invention, Figure 1 is a side elevation of my baling-press. Fig. 2 is a plan view of the power portion. Fig. 3 is a horizontal section of the baling portion. Fig. 4 is a vertical section of the baling-chamber, showing the threading-needles and frame in elevation. Fig. 5 is a 20 vertical longitudinal section showing the follower on its forward movement. Fig. 6 is a sectional view showing the follower on its back-stroke and operating the top door of the feed-chamber. Fig. 7 is a detail of the latch mechanism at one end of the top door. Fig. 8 is a plan of the power-mechanism connections. 25 Fig. 9 is a horizontal sectional view of the power-wheel and its trip. Fig. 10 is a vertical section of said wheel and trip. Fig. 11 is a vertical longitudinal section of the baling-chamber, showing the end door or cap and 30 means for fastening it. Fig. 12 is a detail view of the flap-operating device. Fig. 13 is a detail showing the means for locking the end door disconnected.

35 A is the baling-press frame, in the forward end of which is the baling-chamber B, behind which is the feed-chamber C. The whole frame A is mounted at an incline, its forward end being supported upon wheels a. Within the frame A is the follower D, Figs. 3, 5, and 40 6, having cross-heads, the ends d of which project through the sides of the press in elongated slots therein, whereby the follower moves back and forth, traversing the feed-chamber and entering the baling-chamber. 45 50 This movement of the follower is effected by means of toggle-levers E, which are pivoted to the projecting ends d of the cross-heads of

the follower, and are also pivoted to the frame, and these toggle-levers are operated by means of the main power-chain F, the 55 branches f of which, passing over suitable guide-pulleys f', extend to and are connected with the toggle-levers. By drawing on the chain F the toggle-levers E are straightened, so that they force the follower forward with 60 great force. The follower is returned by again bending the toggle-levers, this movement being effected by means of the branches g of the cable G.

The feed-chamber C has a top door c, and 65 above this is built the feed-hopper H, for which said door serves as a bottom. In the side walls of this hopper are made the curved slots h, and from the sides of the door project the studs c' through the curved slots of the 70 hopper, as shown in Figs. 5 and 6, and these studs are connected with guide-braces c², Fig. 1, on the outside. The studs do not touch the sides of the curved slots at all, but are pivoted in the arms or braces outside the hopper. 75 The opposite ends of these braces are pivoted to the frame. The door is adapted to be turned through a half-revolution and reversed, end for end, by the follower itself, so as to dump its load into the feed-chamber. 80 This operation is accomplished by means of the mechanism shown in Figs. 5, 6, and 7, to which reference is now particularly made. At its forward end the door c is held down normally by a hinged flap I, controlled by a 85 spring i, which holds it out to place over the end of the door. The rear end of the door is held down by a hinged flap J. In the back of this flap is made a socket j, partially covered by a flange or plate j', Figs. 7 and 12, and 90 into this flanged socket fits the hooked end of the latch K, pivoted by means of arms k to an upright bolt k', Figs. 5 and 12. Against the back of the lower arm k a spring k² presses, causing the latch K to engage the flange or 95 plate j' as the flap J drops down to it.

Pivoted at l is a bell-crank lever L, one arm of which is provided with a small anti-friction roller l', bearing under the rear end of the door c. The other arm of the bell-crank 100 lever carries a stud l'', over which is freely slotted the end of a short lever l³, which is pivoted at l⁴ to the bell-crank lever L. A cord or cable d' connects the follower with

the short lever l^3 . Upon the top of the follower close to each end is a catch-piece d^2 , and the ends of the door c are grooved or notched out to engage with these catches. 5 The operation of this mechanism is as follows: Suppose the door c be in its place, as shown in Fig. 5, and the follower D, advancing through the feed-chamber C, pushing the material which is in said chamber before it 10 into the baling-chamber as it moves forward. The flaps I and J hold the door c down. Now, when the follower is nearly home the cable or cord d' becomes taut, and pulling upon the pivoted short lever l^3 causes said lever to move. Its first movement does not affect the bell-crank lever L, to which it is pivoted, because it is freely slotted over said lever, and this first movement merely has the effect of causing the short lever l^3 to come in contact 15 with the lower arm k of the latch K, thereby turning said latch about the bolt k' as a center and removing its hooked end from the flanged socket j of the flap J, thereby releasing said flap. The further movement of the 20 short lever l^3 now begins to affect the bell-crank lever L, and turning it about its pivotal center raises its roller l' under the rear end of the door c and raises said end slightly, depressing its forward end, as shown in the 25 dotted lines in Fig. 5, and allowing the flap J to fall into the notch or groove in the back end of the door, thus holding the door in position while the follower starts back. The follower now returning, its catches d^2 engage the 30 forward notched end of the door c , said end having been thrown down into its path by the raising of the rear end, and as the follower moves back it pushes the door before it, so that turning about its side studs c' , which 35 travel in the curved slots h of the feed-hopper H, said door assumes first the position shown in the dotted lines of Fig. 6, and then the position shown in the full lines in said figure, and remains there until it is pushed 40 down again by hand, having thus turned through a half-revolution and reversed itself end for end. In this movement it drops the load which was on the top of it into the feed-chamber, and the follower is then ready to 45 move forward again, the hinged flaps I and J having sprung to place to hold the door firmly.

The base of the feed-chamber C is provided with a movable floor M. This floor is hinged by its sills to the frame at m and is adapted to move up in line with the bottom of the frame to contract the feed-chamber and to drop down to a horizontal plane, as shown in Figs. 1 and 6, to expand the chamber, being 55 supported and guided suitably in said movement. The object of this is to afford a greater feeding capacity in the first instance, and this is effected by dropping the floor, thereby allowing the material a greater space in the expanded feed-chamber. This dropping of the 60 floor takes place just as the follower has passed through the feed-chamber on its way

to the baling-chamber, and when the follower has returned and turned the top door, as before described, the material is dropped into the feed-chamber and rests upon the floor M, which is then in the position shown in Fig. 6. This dropping of the floor takes place as follows: A pivoted flap m' has a spring m^2 to hold it in place with its upper end under the free end of the floor M, and provided with an upwardly-projecting flange m^3 . Pivoted to the bottom of the follower is a toe-piece d^3 . Now, when the follower is moving forward, as shown in Fig. 5, the toe-piece d^3 drops 80 down through a slot d^4 in the base of the bale-chamber and comes in contact with the flange m^3 of the holding-flap m' and pushes said flap forward from under the end of the floor M, which thereupon drops of its own weight from 85 the position shown in Fig. 5 to the position shown in dotted lines in said figure and in full lines in Fig. 6; but it is obvious that the floor M must be closed again before the follower moves on its forward stroke, so as to raise all 90 the material into the feed-chamber and confine it in said chamber in front of the follower. This movement of the floor is effected by means of the cord or cable N, which is properly directed and attached to levers n , 95 pivoted to links n' , and connected with the floor M. Now, by pulling on the cable N the levers n are operated to throw the floor up to position, where it is held by the spring-controlled flap m' .

In Fig. 4 I show a rectangular frame O, which embraces the frame A at the entrance of the baling-chamber. The sides of this frame O are mounted in suitable sockets o on the sides of the baling-press, so that the frame 105 may be moved up and down. The bottom bar of the frame carries the vertical needles o' , which extend up through slots b in the floor of the baling-chamber and are adapted to pass through the grooves d^3 of the follower 110 and through slots b' in the top of the bale-chamber. The baling wires or ropes are threaded to these needles, and the needles are raised by raising the frame by hand, so that they carry the ends of the wires up into position to be tied, in a manner presently described.

To the end of the baling-chamber B, at the upper end of frame A, is hinged at its top the end door or cap V, Fig. 11. This cap is fastened and released as follows: Under it are bolted the hooks v . W is a rock-shaft mounted in spring-arms w under the end of the baling-chamber and projecting therefrom, said shaft having a crank-lever w' on one end. The 120 shaft is also provided with projecting lugs w^2 . Now, after a bale has been tied and the follower withdrawn the lever w' is raised to rock-shaft W and brings its lugs up against the hooks v , which engage the shaft and hold 125 the cap. These lugs pressing against the hooks v depress the shaft W, its spring-arms w yielding, so that the shaft leaves the hooks 130 and thus frees the cap. As the material for

the next bale enters, the bale previously pressed and tied is pushed out by it, thus raising the cap. When the bale falls from the press, the cap drops by its own weight and fastens itself again by hooking onto the rock-shaft.

The passage of the wires or ropes for tying the bale is as follows: The bottom of the baling-chamber has slots b , and its top has slots b' . The cap V has vertical slots v' , and the follower D has grooves d^3 on its front. One end of the wires or ropes is passed through the bases of the slots v' of the cap, and along in the slots b of the bottom of the baling-chamber, and through the eyes of the needles o' . The other end is passed through the tops of the slots v' of the cap and out through and along the slots b' in the top of the baling-chamber, and is tied to the first end, which has been raised through the slots d^3 of the follower to the top by the needles o' .

In Fig. 8 I have shown the continuation timbers P of the frame A, said timbers diverging rearwardly and having mounted between their separated rear ends the main power-wheel Q, which is adapted to be operated by a power-lever q , Figs. 1 and 2, to the end of which the horses are attached. The rim of the wheel is enlarged and provided with a circumferential groove, as shown in the section, Fig. 10, and upon this enlarged rim is fitted and adapted to slide a bracket R, in which is pivoted at r a trip-lever r' , having an extended base r^2 , which extends down and travels in the groove of the wheel, and a cross-head top r^3 . Pivoted in the bracket R at its other end is a trigger S, having a spring s . To the trip-lever r' is attached the main operating-chain F, which connects with the toggles E, which operate the follower. Transversely mounted on the frame P is a rod or guide p , on which is mounted and adapted to slide a collar p' , held in place and controlled by a link p^2 , operated by a lever p^3 , Fig. 8. The collar p' stands in the path of the trigger S, as shown in Figs. 8 and 9. In the groove of the wheel Q at one place is firmly fixed a contact-block q' , Fig. 9. Now, when the wheel Q is turned by the lever q it does not affect at first the movement of the bracket R and its attached parts; but when the contact-block q' of the wheel comes around to and is brought into contact with the base of the trip-lever r' , as shown in Fig. 9, then these parts are picked up and carried with the wheel, and, moving around with it, draw on the chain F, thereby causing the forward movement of the follower and driving it home; but at this time the trigger S, approaching the fixed collar p' , as is shown in Fig. 8, comes in contact therewith, as is shown in Fig. 9, and is bent over, thereby relieving its lower end from the base of the trip-lever r' , and said trip-lever being free turns about its pivotal center as the stop-block q' passes it, so that the wheel moves on without carrying the trip any far-

ther, and therefore the tension on the chain F is released and the follower ceases to be operated. When the follower is drawn back by the means presently to be described, the bracket R and its connected parts are drawn around on the rim of the wheel Q by the chain F until, coming in contact with the fixed stop q^2 on the opposite side, as is shown in Fig. 9, the trip-lever is thrown up to a vertical position again, and the trigger S, actuated by its spring s , is turned into position and again holds the trip-lever.

The drawing back of the follower, as before stated, is effected by means of the chain or cable G. This chain or cable, as is shown in Fig. 8, passes over a guide-pulley g' and is attached to a pivoted arm T, connected with the frame-timbers P. This arm extends into the path of a fixed pin or stud q^3 under the lever q' , and at the proper time the contact of this stud with the arm T swings said arm and pulls upon the cable G, so as to return the follower.

The upward movement of the floor M of the feed-chamber is effected, as heretofore described, by the cable N. This cable, as will be seen in Fig. 8, passes backwardly over the guide pulley g' , and is attached to the end of the swinging bar or arm U, the projecting end of which lies in the path of a second pin or stud q^4 under the lever q , and when the contact of said pin or stud with the arm U is effected the cord or cable N is pulled upon and raises the floor.

The object of having the collar p' adjustable on its rod p is to vary the position at which the trigger S comes in contact with it. Thus on the final pressure of the bale it is desirable to let the follower move closer home before it is released by the trip, and this is done by setting the collar p' farther back, so that the trigger S will not come in contact with it so soon.

Having thus described my invention, what I claim as new, and desire to secure by Letters Patent, is—

1. In a baling-press, the frame having the feed-chamber and the feed-hopper above it with the curved slots in its sides, in combination with the top door c of the feed-chamber, having side studs mounted in the curved slots of the hopper, a swinging flap for locking the top door in place, the reciprocating follower in the feed-chamber, connections between said follower and the hinged flap for releasing it, and a catch on the follower for coming in contact with the door, whereby it is raised, substantially as described.

2. In a baling-press, the frame having the feed-chamber and the hopper above it with curved slots in its sides, in combination with the reversible top door of the feed-chamber, having side studs fitting in the curved slots of the hopper, the swinging flap I, for holding down the forward end of the door, the swinging flap J, for locking its rear end, the bell-crank lever L, for raising the rear end of the

door and depressing its forward end, the moving follower of the press, the connecting-cord between the follower and the bell-crank lever for operating the latter, and the catch on the follower for coming in contact with the forward end of the door and raising it as it moves back, substantially as described.

3. In a baling-press, the frame having the feed-chamber and the hopper above it with 10 curved slots in its sides, in combination with the reversible top door of the feed-chamber, having side studs fitting in the curved slots of the hopper, the swinging flap I, for holding down the forward end of the door, the swinging flap J, for locking its rear end, the pivoted hook K, for holding the flap J, the bell-crank lever L, for raising the rear end of the door and depressing its forward end, the slotted short lever l^3 , for releasing the hook K and 20 operating the bell-crank lever L, the reciprocating follower, the cord d' , connecting it with the short lever l^3 , and the catch on the follower for coming in contact with the forward end of the door, whereby said door is raised 25 by the follower as it moves back, substantially as described.

4. In a baling-press, the frame having the feed-chamber, in combination with the hinged floor M, for said chamber, the spring-controlled flap having a flange on its upper end 30 for holding the floor up, the reciprocating follower in the feed-chamber, and the toe-piece on the follower for coming in contact with the flange of the flap and releasing it to allow 35 the floor to drop, substantially as described.

5. In a baling-press, the frame having the feed-chamber and the reciprocating follower therein, in combination with the swinging floor of the said chamber and the means for 40 raising it to place, consisting of the chain or cable N, the levers n , and links n' , substantially as described.

6. In a baling-press, the feed-chamber of the frame and the reciprocating follower therein 45 having the toe-piece on its base, in combination with the hinged floor M of the feed-chamber, having an opening through which the toe-piece drops, the spring-controlled flap m' , with flanged top for holding the floor up and 50 relieving it by contact with the toe-piece of the follower, and the means for raising the floor, consisting of the chain or cable N, the lever n , and links n' , substantially as described.

55 7. In a baling-press, and in combination with the chain F, for operating its follower, the grooved power-wheel Q and the lever q , for operating it, the sliding bracket R, mounted on the wheel, the trip-lever r' , pivoted in 60 the bracket and bearing in the grooved periphery of the wheel, said lever being connected with the chain F, and the contact-block q' in the grooved periphery of the wheel for coming against the base of the trip-lever and 65 moving it with it, substantially as described.

8. In a baling-press, the combination of the chain F, for operating its follower, the grooved power-wheel Q, the lever q , for operating the wheel, the sliding bracket R on the wheel, the pivoted trip-lever r' in the bracket and bearing in the grooved periphery of the wheel, said lever being connected with the chain F, the trigger S in the bracket for holding the lever in position, the contact-block q' of the wheel, and the collar p' , against which the lever comes in contact for relieving the trip-lever, substantially as described.

9. In a baling-press, and in combination with the chain F, for operating the follower of the press, the grooved power-wheel Q, the lever q , for operating it, the sliding bracket R on the wheel, the pivoted trip-lever mounted in the bracket and connected with the chain, the trigger S, for holding the trip-lever in place, the contact-block q' of the wheel for 85 moving the lever, and the sliding adjustable collar p' , against which the trigger comes in contact to relieve the trip-lever, substantially as described.

10. In a baling-press, and in combination with the chain F, for operating its follower, the grooved power-wheel Q, the lever q , for operating it, the sliding bracket R on the wheel, the trip-lever pivoted in the bracket and connected with the chain, the spring-controlled trigger S, for holding the lever in place, the contact-block of the wheel for moving the trip-lever, the collar for releasing the trigger and the lever, and the fixed stop q^2 , for straightening the parts up again, substantially as described.

11. In a baling-press having the feed-chamber and the swinging floor M, for said chamber, the cord or cable N, and intermediate connections for raising the floor, the swinging arm U, to which said cord or cable is attached, and the revolving lever q , having a stud or pin adapted to come in contact with the swinging arm U, substantially as described.

12. A baling-press consisting of the frame, the follower within said frame, the toggle-levers E, for operating the follower, and the hinged floor M of the feed-chamber, the grooved wheel Q, having a lever q , for operating it, the pivoted sliding trip on the wheel, the chain F, connected with said trip and with the toggle-levers of the press, the pivoted arms U T and cables N G, connecting them, respectively, with the floor of the feed-chamber and the toggle-levers of the follower, and the studs on the lever q , for operating the arms U T, substantially as described.

In witness whereof I have hereunto set my hand.

WALTER BULLARD.
